UNITED STATES PATENT OFFICE

RALPH K. MERRILL, OF GRAND RAPIDS, MICHIGAN, ASSIGNOR TO AMERICAN SEATING COMPANY, OF GRAND RAPIDS, MICHIGAN, A CORPORATION OF NEW JERSEY

DESK TOP

Application filed October 5, 1929. Serial No. 397,494.

The present invention relates to desk tops, particularly such as are used in schools; and its object is, generally, to provide an improved structure of that character; and more particularly to provide in such a structure an improved lid portion which may be opened to afford access to the box or container thereunder and may also be raised to, and supported in, an inclined position wherein it forms a support for books and the like; and further, to provide improved constructional features in such a structure.

This and any other and more specific objects hereinafter appearing are attained by, and the invention finds preferable embodiment in, the desk top structure hereinafter particularly described in the body of this specification and illustrated by the accompanying drawings, in which:

20 Figure 1 is a transverse vertical medial sectional view of a box top of a desk showing the closure or lid portion raised to open position to afford access to the box or container beneath;

25 Figure 2 is a front view of the left hand end portion thereof, said box being sectioned longitudinally vertically on line 2—2 of Figure 1;

30 Figure 3 is an enlarged cross sectional view of certain parts taken on line 3—3 of Figure 1;

35 Figure 4 is a transverse vertical medial sectional view of said structure showing the lid portion raised to book-supporting position; and

Figure 5 is a sectional view of certain parts taken on line 5—5 of Figure 4.

The box top for a school desk illustrated by these drawings is supported by suitable legs (not shown) and comprises a box or receptacle 1 having a front wall 2, rear wall 3, end walls and bottom—all of any usual form and construction—and a cover or top which comprises a stationary front portion 4 in fixed relation with said front wall and a movable closure or lid portion 5. These cover portions are connected by hinges, one of whose leaves 6 is fastened to the stationary portion 4, the other leaf 7 extending rearwardly toward the rear wall 3. An elongated element 8 has flanges 9 secured as by screws 10 to the under side of the lid portion 5 and extends transversely thereof; a second elongated element 11 bears slidably in element 8 and is pivotally connected at its rear end at 12 to the rear end of the second-mentioned leaf 7 of the hinge. A link 13 is pivotally connected at one end at 14 to the forward end of the second-mentioned leaf 7 and at its other end is connected at 15 medially of the lid portion, i. e. medially of the element 8.

These parts—the said elements 8 and 11, the leaf 7 of the hinge, and the link 13—are hollow, having vertical flanges and are folded together into compact flat form in the shut down position of the lid portion 5 and as shown in Figure 3. A coiled expansion spring 16 inside the hollow elements 8 and 11 and pressing against abutments 17, 18 thereof urges these elements longitudinally apart to the position seen in Figure 4.

When the lid portion 5 is lowered into shut down position on the box or receptacle 1, thus closing the same, its front edge 19 is in abutting relation with the rear edge 20 of the stationary portion 4 of the top, and is releasably engaged therewith by a spring-pressed ball latch 21. In this shut down position of the lid portion 5, its rear edge portion and the leaf 7 are supported on an elastic member 22 carried inside the box by the bent-over lip 23 of the rear wall 3. Secured to the under side of the lid near its forward position is a segment 24 bearing on a friction element in a casing 25, carried by the box's end wall, to frictionally hold the lid portion in raised position shown in Figure 1.

The structure has the following uses and operation: In the shut down position of the lid portion 5 shown in dotted lines in Figure 1, it covers and conceals papers, books and other articles contained in the box 1 and the upper surface of the lid portion provides a table surface for writing, etc. When it is desired to gain access to the box to remove or insert articles thereinto, the lid portion is raised to the position shown in solid lines in said view, the leaf 7 in this movement being carried with the lid portion. When it is de-

sired to provide a support for a book or the like while the same is being read or examined, the leaf 7 remains in its approximately horizontal position seen in Figure 4 while the 5 lid portion carrying element 8 is at its forward edge 19 raised out of engagement with the stationary portion 4, whereupon the spring 16 (now permitted to expand) urges the lid portion upwardly and forwardly into the inclined position shown in Figure 4, 10 in which the upwardly carried link 13 supports it as a strut. The movable ledge 26 may be slid along its inclined slots 27 to 15 raised position to support the books, papers, etc. on the inclined lid portion 5.

18 The invention being intended to be pointed out in the claims, is not to be limited to or by details of construction of the particular embodiment thereof illustrated by the drawings or hereinbefore described.

20 I claim:

1. In a desk top: a stationary front portion; a movable lid portion; a hinge comprising a leaf secured to the front portion 25 and a rearwardly extending leaf; an elongated element secured to the under side of the lid portion and extending forwardly-rearwardly thereof; an elongated element in slidably bearing relation to the first-mentioned element and pivotally connected at its rear end to the rear end of the second-mentioned leaf; a link pivotally connected to the forward end of the second-mentioned leaf and to the lid portion.

35 2. In a desk top: a stationary front portion; a movable lid portion; a hinge comprising a leaf secured to the front portion and a rearwardly extending leaf; an elongated element secured to the under side of the lid portion and extending forwardly-rearwardly thereof; an elongated element in slidably bearing relation to the first-mentioned element and pivotally connected at its rear end to the rear end of the second-mentioned leaf; a link pivotally connected to the forward end of the second-mentioned leaf and to the lid portion; an expansion 40 spring urging said elements longitudinally apart.

50 3. In a desk top: a stationary front portion; a movable lid portion abutting in its shut down position on said front portion; a hinge comprising a leaf secured to the front portion and a rearwardly extending leaf; an elongated element secured to the under side of the lid portion and extending forwardly-rearwardly thereof; an elongated element in slidably bearing relation to the first-mentioned element and pivotally connected at its 55 rear end to the rear end of the second-mentioned leaf; a link pivotally connected to the forward end of the second-mentioned leaf and to the lid portion.

60 4. In a desk top: a stationary front portion; a movable lid portion releasably en-

gaging in its shut down position said front portion; a hinge comprising a leaf secured to the front portion and a rearwardly extending leaf; an elongated element secured to the under side of the lid portion and extending forwardly-rearwardly thereof; an elongated element in slidably bearing relation to the first-mentioned element and pivotally connected at its rear end to the rear end of the second-mentioned leaf; a link pivotally connected to the forward end of the second-mentioned leaf and to the lid portion.

65 5. In a desk top: a stationary front portion; a movable lid portion; a hinge comprising a leaf secured to the front portion and a rearwardly extending leaf; an elongated hollow element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof; a spring in 70 said elements urging the same longitudinally apart.

75 6. In a desk top: a stationary front portion; a movable lid portion; a hinge comprising a leaf secured to the front portion and a rearwardly extending leaf; an elongated hollow element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof; a spring in 80 said elements urging the same longitudinally apart.

85 7. In a desk top: a stationary front portion; a movable lid portion; a hinge comprising a leaf secured to the front portion and a rearwardly extending leaf; an elongated hollow element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof, the link and the second-mentioned leaf being folded together into flat form in the shut down position of the lid portion.

90 8. In a desk top: a stationary front portion; a movable lid portion; a hinge comprising a leaf secured to the front portion and a rearwardly extending leaf; an elongated hollow element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof, the link having lateral flanges receiving the first-mentioned element and the second-mentioned leaf having lateral flanges receiving the link in the shut down position of the lid portion.

95 9. In a desk top: a stationary front portion; a movable lid portion; a hinge comprising a leaf secured to the front portion and a rearwardly extending leaf; an elongated hollow element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof, the link having lateral flanges receiving the first-mentioned element and the second-mentioned leaf having lateral flanges receiving the link in the shut down position of the lid portion.

low element secured to the under side of the lid portion and extending forwardly-rearwardly thereof; an elongated hollow element slidably bearing in the first-mentioned element and pivotally connected at its rear end to the rear end of the second-mentioned leaf; a link pivoted to the forward end of the second-mentioned leaf and to the first-mentioned element medially thereof, the first-mentioned element, the link and the second-mentioned leaf being folded together into flat form in the shut down position of the lid portion; a spring urging said elements longitudinally apart.

9. In a structure of the character described: an open-top box; a closure therefor; a hinge comprising a leaf in fixed relation with the front end of the box and a rearwardly extending leaf; an elongated element slideable forwardly-rearwardly on the closure, said element being pivotally connected at its rear end to the rear end of the second-mentioned leaf.

10. In a structure of the character described: an open-top box; a closure therefor; a hinge comprising a leaf in fixed relation with the front end of the box and a rearwardly extending leaf; an elongated element slideable forwardly-rearwardly on the closure, said element being pivotally connected at its rear end to the rear end of the second-mentioned leaf; an expansion spring between a member carried by the closure and said element pressing said element rearwardly.

11. In a structure of the character described: an open-top box; a closure therefor; a hinge comprising a leaf in fixed relation with the front end of the box and a rearwardly extending leaf; an elongated element slideable forwardly-rearwardly on the closure, said element being pivotally connected at its rear end to the rear end of the second-mentioned leaf; an expansion spring between a member carried by the closure and said element pressing said element rearwardly; a strut pivoted to the closure member and the second-mentioned leaf.

In testimony whereof I have hereunto set my hand at Grand Rapids, Michigan, this 2nd day of October, 1929.

RALPH K. MERRILL.
